UNITED STATES PATENT OFFICE.

ANDREW FAIST, OF SAN FRANCISCO, CALIFORNIA, ASSIGNOR OF THREE-FOURTHS
TO LOUISE GRIEGER, OF SAN FRANCISCO, CALIFORNIA.

WIRE-STRETCHER.

1,367,129.

Specification of Letters Patent.

Patented Feb. 1, 1921.

Application filed February 7, 1920. Serial No. 356,835.

To all whom it may concern:

Be it known that I, ANDREW FAIST, a citizen of the United States, residing at San Francisco, in the county of San Francisco and State of California, have invented certain new and useful Improvements in Wire-Stretchers, of which the following is a specification, reference being had to the accompanying drawings.

10 This invention relates to an improved wire stretcher for stretching various wires regardless of where they are located, for instance, telephone, telegraph and fence wires, particularly the latter, and an object 15 of the invention is to provide a device of this kind, which is simple, efficient and practical and comprises novel features of construction, and also to provide a machine which can be manufactured for a relatively 20 low cost and sold at a reasonable profit.

Another object of the invention is to provide a wire stretcher which is capable of stretching wire, either from the right to the left, or from left to right.

25 Another object of the invention consists in the provision of a clamp, and an intermittently operative mechanism swiveled thereto, whereby, as the wire is being stretched, it may be turned back toward the 30 post, in case the post should happen to twist when stretching the wire, and furthermore, by the provision of the swivel connection, the stretching machine may be kept in alinement with the wire, so that the wire 35 may at all times travel straight into the machine.

A further object of the invention is to provide a machine of this kind, so used for stretching wires, as to permit the wire to 40 be nailed or otherwise fastened to the same post, from which the wire is stretched, thereby saving much labor and inconvenience, by doing away with having to brace two posts.

45 A still further object of the invention resides in the provision of a stretcher that will prevent the twist or turn of the post, before the stretcher is detached from the post, thereby leaving the wire stretched the 50 same as when the machine stretched it.

The invention still further aims to provide a stretcher which is capable of stretching the wire under all conditions, such as inside of sharp fence corners, in brush or 55 among trees, as the operating lever of the

machine can be manipulated in either a vertical or horizontal position, or any degree between such positions.

The invention additionally aims to provide a stretcher which can be easily and 60 very quickly attached to a post, and will complete stretching the wire up to the corners and ends of the fence.

While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

The invention comprises further features and combination of parts, as will be herein-after set forth, shown in the drawings and 75 claimed.

In the drawings:

Figure 1 is a view in elevation of a portion of a wire fence, showing the wire stretcher as applied to one of the posts of 80 the fence for stretching one of the fence wires,

Fig. 2 is a plan view of one of the fence posts on an enlarged scale, showing the wire stretcher applied,

Fig. 3 is a vertical sectional view on line 3—3 of Fig. 2,

Fig. 4 is a vertical sectional view on line 4—4 of Fig. 1,

Fig. 5 is a sectional view on line 5—5 of 90 Fig. 3,

Fig. 6 is an enlarged detail perspective view of the clamping bar 2, and showing the clamping claw,

Fig. 7 is a detail perspective view of the 95 frame 9, and showing the detent spring 37, and also the detent releasing device,

Fig. 8 is a detail perspective view of the detent releasing crank element 40, and

Fig. 9 is a detail view in elevation of the 100 lever 33 showing the spring tensioned rod for coöperation with the ratchet 25.

Referring more especially to the drawings, 1 designates a clamp, which comprises a bar 2 provided with a right angle extending plate 3 at one end which bears against the fence post when stretching a fence wire. Mounted upon the bar 2 is a clamp 4 to co-operate with the plate 3 to hold the clamp 1 to the post. The clamp 4 is constructed 110

of a single piece of metal bent upon itself to form a rectangular loop 5, which receives the bar 2 of the clamp 1. The opposing parts of the clamp 4 are riveted together 5 as indicated at 6, and the end portions of the opposing parts terminate in claws 7, adapted to bear into the fence post and co-operate with the opposing plate 3, to hold the clamp securely and firmly to the post. 10 A set screw 8 is threaded into the loop of the clamp 4 to hold the clamp in different adjusted positions on the bar 2.

A U-shaped frame 9 is swivelly connected to the plate 3 by means of the headed pin 15 10, the head of which is counter-sunk in one face of the plate 3. A suitable washer 11 is interposed between one end of the frame 9 and the plate 3. A cotter pin 12 passes through the headed pin 10 to hold the same 20 in position.

Journalized upon a shaft 13 which is mounted in slot bearings of the sides of the frame 9 is a wheel 14. This wheel has a groove 15 in its periphery, and formed on one face of the wheel are gear teeth 16. A dowel pin 17 passes transversely through one end of the shaft 13, and is counter-sunk in the outer face of one of the sides of the frame 9 (which is U-shaped) to prevent the shaft 30 from rotating, whereas the wheel is rotatable upon the shaft. A cotter pin 18 passes transversely through the opposite end of the shaft 13 to coöperate with the dowel pin to prevent axial movement of the shaft. The 35 ends of the sides of the frame 9 are bifurcated as shown at 19, and are provided with forks 20 caused to be formed by the bifurcations. Removably engaging between the forks are anti-frictional rollers or sleeves 21, which constitute bearings for the shaft 22. Feathered or splined to the shaft 22 as at 23 is a wheel 24, which comprises three sections 25, 26 and 27, which are fastened together by the transverse pins 28. The section 25 of the 40 wheel is provided with ratchet teeth 29, and the section 26 is smaller in diameter than the section 27, and is provided with gear teeth 30. The section 27 is also provided with gear teeth 31, which are adapted to mesh with the gear teeth 16 of the wheel 14, when the wheel 24 is moved toward the wheel 14. Pivoted upon one of the sleeves 21 to move relatively thereto and positioned adjacent the side of the wheel 24 is the flat end 32 of the lever 33. Mounted on one face of the lever 33 is a dog 35, adapted to engage the ratchet teeth 29 of the section 25 of the wheel 24, so as to impart an intermittent movement to the wheel.

60 A spring detent 37 has the terminal of the curved portion counter-sunk in and secured to one end of the frame 9. This spring detent extends in a direction with the frame 9 and terminates in a lug 38, which is designed to coöperate with the ratchet teeth of the

section 25 of the wheel 24, to prevent retrograde movement of the wheel, as it is intermittently moved by the manipulation of the lever. An arm 39 is fastened rigidly to one side of the frame 9, and mounted in a bearing of said arm is a crank element 40. This crank element has a projection 41, which is adapted to cam against the spring detent, in order to disengage the lug of the spring detent from engagement with the ratchet teeth 75 of the wheel 24.

In the operation of the machine, it is first mounted upon the fence post and secured rigidly in position by means of the clamp 1, although the frame 9 is capable of swivel movement. The usual fence wire reel is arranged as shown in Fig. 1, with the fence wire, which may be barbed or plain, passed upwardly over the wheel 14, and downwardly between the wheel 14 and the teeth 30 of the wheel 24, and then over the gear teeth 30 between the ratchet teeth and the gear teeth 31, and then adjacent the fence post, and to the other fence post, as shown. In order to stretch the fence wire, the lever is moved in the direction of the arrow α which will impart an intermittent motion to the wheel 24, stretching the fence wire.

Each movement of the wheel 24 will tension the fence wire, and by means of the spring detent, the wheel 24 is prevented from retrograde movement. Should the wire be stretched to an excess and it is desired to release the tension of the wire, the detent may be disengaged from the wheel or ratchet 24, and then by grasping the lever 33 and holding the same while it moves backward, the wire may be allowed to slacken. When the wire is slackened enough, the detent will be allowed to again engage the ratchet to hold the same. The spring tensioned dog comprises a rod 35 mounted in guide eyes 36^a and 37^a which are carried by one side of the lever 33. A coiled spring 38^a is in surrounding relation to the rod or dog 35 and is interposed between the guide eye 36^a and a cotter pin 39^a which is arranged transversely of the rod 35. The cotter pin is spaced slightly from the eye 37^a so that the spring 38^a may tension the rod to hold its end 40^a in engagement with the teeth of the ratchet. The ends of the rod opposite its end 40^a terminates in a hook 4^a which may be engaged by the finger of the operator, in order to disengage its end 40^a from the teeth of the ratchet.

After the wire has been stretched, it is not released until it is fastened to the fence post, and it is the aim to fasten the fence wire to the same post from which the wire is stretched, thereby saving much labor and inconvenience.

In order to additionally fasten the clamp 1 to the fence post, a short nail or staple may be driven through any one of the several

openings or holes in the plate 3, and then into the fence post, as indicated at 42.

The wire stretcher may be connected to the fence post so that the fence wire may be nailed or fastened to the very top of the post, if desired. Also the wire may be fastened to the extreme lower portion of the post. This may be accomplished by excavating the ground around the post, so as to counter-sink the stretcher, so that the fence wires may be stretched immediately from a close position to the ground and disposed close together, in order to prevent the passage of hogs, rabbits and the like. The stretcher can be easily removed from the post, by pulling outwardly upon the bar 2, that is after the clamp 4 has been disengaged from the post, thereby causing the plate 3 to extract the nail.

Furthermore, the stretcher will not injure the fence wire, when stretching the same, which is very often the case with all other stretchers, due to the wire passing around a wheel and causing friction. The present form of wire stretcher may be used for other purposes, such as pulling automobiles back into the roadway at rough places, and for pulling stumps, posts and trees, or large bushes. When pulling automobiles back into the roadway, the stretcher may be attached to a stationary object, and after which a heavy cable or chain or the like may be attached to the automobile and passed over the stretcher in the same manner as the wire to be stretched is arranged, after which the usual intermittent motion is imparted to the wheel 24. This device can be used also for pulling bushes and hoisting commodities. When pulling bushes or hoisting commodities, the device may be mounted or connected to a pair of vertically arranged spaced stakes, and the cable or chain is then passed downwardly and around the bush and by manipulating the lever, it may be extracted from the soil.

In order to direct the wire back toward the fence post, should the fence post become twisted, due to the strain of the wire, the U-shaped frame may be moved swivelly, by applying pressure laterally upon the lever in a direction of the fence post. Owing to the swivel connection with the U-shaped frame, it is possible to keep the fence wire at all times in alinement with the feed wheels.

The invention having been set forth, what is claimed as new and useful is:

1. In a wire stretcher, the combination with a supporting frame adapted to be rigidly connected to a stationary member, of a second frame provided with slotted bearings for a feed wheel swivelly mounted on the first frame, of a feed wheel rotatably mounted in the second frame, a second feed wheel mounted to slide in bearings of said

second frame and being intermittently rotatable, gear connections between the two feed wheels, and means for imparting intermittent motion to the second feed wheel, whereby a wire or the like may be fed over the second feed wheel and between the two feed wheels.

2. In a wire stretcher, the combination with a supporting frame adapted to be rigidly connected to a stationary member, of a second frame provided with slotted bearings for a feed wheel swivelly mounted on the first frame, of a feed wheel rotatably mounted in the second frame, a second feed wheel mounted to slide in bearings of said second frame and being intermittently rotatable, gear connections between the two feed wheels, means for imparting intermittent motion to the second feed wheel, whereby a wire or the like may be fed over the second feed wheel and between the two feed wheels, and a detent or holding means for the second feed wheel.

3. In a wire stretcher, the combination with a supporting frame adapted to be rigidly connected to a stationary member, of a second frame provided with slotted bearings for a feed wheel swivelly mounted on the first frame, of a feed wheel rotatably mounted in the second frame, a second feed wheel mounted to slide in bearings of said second frame and being intermittently rotatable, gear connections between the two feed wheels, means for imparting intermittent motion to the second feed wheel, whereby a wire or the like may be fed over the second feed wheel and between the two feed wheels, and a detent or holding means for the second feed wheel, and means for actuating the detent or holding means to release the second feed wheel.

4. In a wire stretcher, the combination with a supporting frame rigidly mounted upon a stationary member, of a second frame connected to the first frame, a feed wheel rotatably mounted in the second frame, a second feed wheel mounted in the second frame and being intermittently rotatable, gear connections between the two feed wheels, said feed wheels having wire receiving means, whereby a wire is adapted to pass over the second feed wheel and then upwardly between both feed wheels and over the first feed wheel, and means for imparting intermittent rotatable movements to the second feed wheel, for stretching the wire, and holding means for the second feed wheel.

5. In a wire stretcher, the combination with a supporting frame rigidly connected to a stationary member, of a U-shaped frame swivelly mounted on the first frame, a feed wheel rotatably mounted between the sides of the U-shaped frame, a second feed wheel mounted in the second frame and being in-

5 intermittently rotatable, gear connections between both wheels, said wheels having wire receiving means, whereby wire to be stretched is adapted to pass over the second feed wheel, under and upwardly between both feed wheels and over the first feed wheel, means for imparting an intermittent motion to the second feed wheel, and manually released holding means for preventing 10 retrograde movement of the second feed wheel.

6. In a wire stretcher, the combination with a supporting frame rigidly mounted upon a stationary member, of a U-shaped frame swivelly mounted upon the supporting frame, a feed wheel rotatably mounted 15 in the U-shaped frame, a second feed wheel

disposed between the sides of the U-shaped frame and having gear connections with the first feed wheel, means for imparting an 20 intermittent motion to the second feed wheel, means for mounting the second feed wheel slidably in the sides of the U-shaped frame, said feed wheels having wire receiving means, whereby the wire is adapted to 25 pass over the second feed wheel and under and upwardly between both wheels, and manually released detent means to prevent retrograde movement of the second feed wheel.

30 In testimony whereof I hereunto affix my signature.

ANDREW FAIST.
